UNITED STATES PATENT OFFICE.

DAVID LEVOW, OF NEW YORK, N. Y.

DESIGN FOR A LEADER STRAP.

Application filed March 24, 1928. Serial No. 25,988. Term of patent 14 years.

To all whom it may concern:

Be it known that I, DAVID LEVOW, a citizen of the United States, residing in the borough of Manhattan, in the city, county, and State of New York, have invented a new, original, and ornamental Design for Leader Straps, of which the following is a specification, reference being had to the accompanying drawing, forming part thereof.

I claim:

The ornamental design for a leader strap as shown and described.

DAVID LEVOW.
